Patented Sept. 2, 1969

215,132

POWER UNIT FOR A BLENDER OR THE LIKE

Thomas E. Hanson and Paul D. Younge, Syracuse, N.Y.,
assignors to Proctor-Silex Incorporated, Philadelphia,
Pa., a corporation of New York

Filed May 14, 1968, Ser. No. 11,937

Term of patent 14 years

Int. Cl. D7—05

U.S. Cl. D89—1

FIG. 4

FIG. 1

FIG. 2

FIG. 3

FIG. 5

FIG. 6

FIG. 8

FIG. 7

FIGURE 1 is a perspective view of a power unit for a blender or the like embodying our new design;

FIGURE 2 is a front elevational view thereof;

FIGURE 3 is a left side elevational view thereof;

FIGURE 4 is a top plan view thereof;

FIGURE 5 is a right side elevational view thereof;

FIGURE 6 is a rear elevational thereof;

FIGURE 7 is a perspective view of a power unit for a blender or the like, showing another form of our new design;

FIGURE 8 is a left side elevational view thereof;

FIGURE 9 is a right side elevational view thereof; and

FIGURE 10 is a front elevational view thereof.

The dominant features of our design reside in the portions shown in full lines.

We claim:

The ornamental design for a power unit for a blender or the like, as shown and described.
